CURVED COURSE SHROUD TO COVER BOAT PROPELLER SHAFT AND SHAFT BEARING

Robert W. Read, 5405 104th St. SW., Tacoma, Wash.
98499, and David C. Knowlen, Tacoma, Wash.; said
Knowlen assignor to said Read

Filed May 1, 1972, Ser. No. 249,471

Term of patent 14 years

Int. Cl. D12—99

U.S. Cl. D12—60

FIG. 1

FIG. 2

FIG. 3

FIG. 4

FIG. 5

FIG. 1 is a perspective view of a curved course shroud to cover boat propeller shaft and shaft bearing showing my new design;

FIG. 2 is a bottom view thereof, the top being a plain flat surface;

FIG. 3 is a side elevational view thereof, the opposite side being the same;

FIG. 4 is a front elevational view thereof, and FIG. 5 is a back elevational view thereof.

We claim:

The ornamental design of a curved course shroud to cover boat propeller shaft and shaft bearing, as shown and described.
